UNITED STATES PATENT OFFICE.

WILLIAM ANDERSON, OF ST. LOUIS, MISSOURI, ASSIGNOR OF ONE-FIFTH TO MARY OLIVER AND ONE-FIFTH TO JOHN CULLINANE.

WINDOW FIXTURE.

Application filed December 22, 1927. Serial No. 241,924.

The invention relates to improvements in fixtures for holding shade rollers, curtain rods, drapery rods, etc. at the upper ends of window frames, and it is the principal object 5 of my invention to provide a new and improved device of this character which may be constructed throughout, from wire, thus economizing in material and manufacturing expense, but still producing an article which 10 may be made very attractive, for instance, if constructed from brass wire or if nickel-plated.

With the foregoing in view, the invention resides in the novel subject matter herein- 15 after described and claimed, and illustrated in the accompanying drawing.

Fig. 1 is a top plan view showing the invention in use for supporting a shade roller, a curtain rod and a drapery rod.

20 Figs. 2, 3 and 4 are vertical transverse sectional views on the correspondingly numbered lines of Fig. 1.

Fig. 5 is a perspective view of the fixture.

The fixture herein disclosed consists of two 25 members 6—6^a slidably connected with each other and of identical construction except that they are "rights" and "lefts." Hence, a description of the member 6 will suffice.

In constructing the member 6, I make use 30 of a single piece of stiff wire. This wire is bent upon itself at 7 near one end, providing an upper relatively long reach 8 and a lower comparatively short reach 9. Near the bend 7, the long reach 8 has portions which extend 35 first laterally outward and then again inwardly, providing two supporting arms 10—11 for a curtain rod 12 and a drapery rod 13 respectively, said arms being receivable in the usual tubular rods as will be clear 40 from Fig. 1.

The wire at the inner end of the reach 9 is directed upwardly and extended above the reach 8 providing a hook shank 14, at whose upper end the wire is bent laterally at 15 and downwardly at 16, providing a supporting hook 45 to engage the upper edge of the trim at the upper end of a window frame. The shank 14 is provided with a portion which extends first outward and then inward, providing a supporting arm 17 for one end of a shade roller 18, the outwardly and inwardly 50 extending portions of said arm 17, being disposed respectively over and under the long reach 8, these portions being identified in the drawing at 17^a and 17^b.

The two long reaches 8 of the two members 6—6^a, are disposed in parallel overlapping relation with each other and at their free ends, are bent to provide eyes 19—19^a, the eye of each reach slidably receiving the other 60 reach so that the two members 6—6^a may be extended a greater or lesser amount, according to the width of the window.

If desired, solder may be used at places where such use would be of advantage, but 65 whether this be done or not, the fixture is nevertheless rigid and efficient, regardless of its simple and inexpensive nature.

On account of the advantages existing for the exact details disclosed, they are prefer- 70 ably followed. However, within the scope of the invention as claimed, minor variations may of course be made.

I claim:

1. In a window fixture, a member formed 75 of a piece of wire bent substantially upon itself near one end to provide an upper relatively long reach and a lower comparatively short reach, one of said reaches having a 80 portion which extends first laterally outward and then inward to form a supporting arm for a curtain or drapery rod, the wire at the inner end of said short reach being bent upwardly and downwardly to form a supporting hook.

2. In a window fixture, a member formed 90 of a piece of wire bent substantially upon itself near one end to provide an upper relatively long reach and a lower comparatively short reach, the wire at the inner end of said short reach being bent upwardly and extended above the long reach to form a hook shank, the wire at the upper end of said 95 shank being bent laterally and downwardly to form a supporting hook, said shank having a portion bent first laterally outward and then inward to provide a supporting arm for a shade roller.

3. In a window fixture, a member formed 100 of a piece of wire bent substantially upon itself near one end to provide an upper relatively long reach and a lower comparatively short reach, the wire at the inner end of said short reach being bent upwardly and extended above the long reach to form a hook shank, the wire at the upper end of said shank being bent laterally and downwardly 105 to form a supporting hook, said shank having 110

a portion bent first laterally outward and then inward to provide a supporting arm for a shade roller, the outwardly and inwardly extending portions of said roller supporting arm being disposed respectively over and under said long reach.

4. In a window fixture, a member formed of a piece of wire bent substantially upon itself near one end to provide an upper relatively long reach, a lower comparatively short reach and a vertical shank extending from the lower reach to a point above the upper reach, one of said reaches having a portion which extends first laterally outward and then inward to form a supporting arm for a curtain or drapery rod, said shank having a portion bent first laterally outward and then inward to provide a supporting arm for a shade roller.

5. In a window fixture, a member formed of a piece of wire bent substantially upon itself near one end to provide an upper relatively long reach, a lower comparatively short reach and a vertical shank extending from the lower reach to a point above the upper reach, one of said reaches having a portion which extends first laterally outward and then inward to form a supporting arm for a curtain or drapery rod, said shank having a portion bent first laterally outward and then inward to provide a supporting arm for a shade roller, the outwardly and inwardly extending portions of said roller supporting arm being disposed respectively over and under said long reach.

6. A structure as specified in claim 1; the free end of said long reach being provided with an eye to slidably engage a similar reach of a complementary member.

7. A structure as specified in claim 2; the

free end of said long reach being provided with an eye to slidably engage a similar reach of a complementary member.

8. A structure as specified in claim 4; the free end of said long reach being provided with an eye to slidably engage a similar reach of a complementary member.

9. In a window fixture, a horizontal wire having an open horizontally elongated frame at one end to lie against the inner side of a window frame, a hook shank rising from said frame and having a hook at its upper end to engage the trim at the upper end of the frame, and roller and rod supporting arms projecting laterally from said frame.

10. In a window fixture, a member formed of a piece of wire bent substantially upon itself near one end to provide an upper relatively long reach and a lower comparatively short reach spaced from and parallel to said upper reach, said upper reach having portions which extend first laterally outward and then inward to form two supporting arms for a curtain rod and a drapery rod, the wire at the inner end of said short reach being bent upwardly and extended above the long reach to form a hook shank, the wire at the upper end of said shank being bent laterally and downwardly to form a supporting hook, said shank having a portion bent first laterally outward and then inward to provide a supporting arm for a shade roller, the outwardly and inwardly extending portions of said roller supporting arm being disposed respectively over and under said upper long reach.

In testimony whereof I have hereunto affixed my signature.

WILLIAM ANDERSON.
